Filed Dec. 12, 1960, Ser. No. 63,195

Term of patent 3½ years

(Cl. D3—4)

FIGURE 1 is a front perspective view of a knitted shirt showing my new design;

FIGURE 2 is a rear view thereof;

FIGURE 3 is a side view thereof showing the sleeve of the shirt in raised position;

FIGURE 4 is a side view of the shirt similar to FIGURE 3 but showing the sleeve of the shirt in lowered position.

My design is characterized by the provision of three relatively coarse rib-knitted bands of substantially uniform width inserted in the sides, sleeves and shoulders of a knitted shirt to provide a contrast between said coarse knitted bands and the remaining knit portions of the shirt, one such band extending continuously along the outer sides of the sleeve portions of the shirt and across the shoulder portions thereof, while the remaining bands each continuously extends along substantially the full length of a side of the body portion of the shirt upwardly to and through the armpit and thence downwardly along the inner side of the adjoining sleeve portion to the hem or cuff thereof.

I claim:

The ornamental design for a knitted shirt, as shown and described.
